UNITED STATES PATENT OFFICE.

CLARENCE E. KELLY, OF ANDERSON, INDIANA, ASSIGNOR OF ONE-HALF
TO WILLIAM H. FORSE, JR., OF ANDERSON, INDIANA.

OPERATING MEANS FOR SPEED-INDICATORS.

SPECIFICATION forming part of Letters Patent No. 716,722, dated December 23, 1902.

Application filed November 14, 1901. Serial No. 82,206. (No model.)

To all whom it may concern:

Be it known that I, CLARENCE E. KELLY, a citizen of the United States, and a resident of Anderson, in the county of Madison and State 5 of Indiana, have invented a new and Improved Operating Means for Speed-Indicators, of which the following is a full, clear, and exact description.

This invention relates to a means for transmitting movement to a speed-indicating device—such, for example, as that disclosed in my copending application, Serial No. 82,203, filed November 14, 1901.

This specification is a specific description 15 of two forms of the invention, while the claims are definitions of the actual scope thereof.

Reference is to be had to the accompanying drawings, forming a part of this specification, in which similar characters of reference indicate corresponding parts in all the views.

Figure 1 is a side view of the invention. Fig. 2 is a top view thereof. Fig. 3 is a section showing the interior of the casing, and Fig. 4 is a similar view showing a modified 25 form of the invention.

In the drawings, *a* may be taken to indicate any known means for imparting a longitudinal movement to the shaft *a'*, such movement being in time with the movement of the 30 part whose speed is to be measured. An example of such means *a* may be seen in my copending application for patent on speed-indicators, Serial No. 79,169, filed October 18, 1901.

Referring to Figs. 1, 2, and 3, the shaft *a'* 35 extends into a casing *b*, which casing is held stationary by a clamp or bracket *f*, and from the casing *b* a shaft *c* extends at right angles to the shaft *a'*. This shaft *c* is adapted to be 40 turned to transmit its movement to the speed-indicator proper. (Not shown.) On the shaft *c*, within the casing *b*, is an arm *c'*, and this arm is engaged by the shaft *a'*, so that upon the reciprocation of this shaft the shaft *c* will 45 be turned. *d* indicates a leaf-spring which bears against a pin *a²* on the shaft *a'*. The tension of this spring *d* is controlled by a cam *e*, fastened on an arbor *e'*. The arbor is mounted to turn in the casing *b* and is provided (see Fig. 2) with a finger *e²*, located outside of the casing *b*, but within an auxiliary

glass-covered case *e³*. (See Figs. 1 and 2.) The top of the casing *e³* is removably held in place by screws or other fastening devices *e⁴*, and by removing this top the finger *e²* may be 55 reached and the cam *e* adjusted, so as to vary the tension of the spring *d* in accord with the conditions under which the wheel *a* is rotated.

Fig. 4 illustrates a modification of the invention, in which the shaft *a'* of the wheel *a* acts on a bell-crank lever *c²*. This lever is fulcrumed at the point *c³* and has a toothed sector *c⁴* meshed with a pinion *c⁵* on the shaft *c*. *d'* indicates a helical spring which is connected to the bell-crank lever *c²* and serves the function of the spring *d* in Figs. 1, 2, and 3, before described. This spring is adjusted by means of an arbor *e⁶*, to which its inner end is attached, such arbor being arranged 65 exactly the same as the arbor *e'*, before described.

Having thus described my invention, I claim as new and desire to secure by Letters Patent—

1. An operating means for speed-indicators, comprising a casing or support, a shaft mounted to reciprocate therein, means for moving said shaft inward, a spring tending to move the shaft outward, a second shaft for transmitting the movement of the first-named shaft, said second shaft being mounted in the casing at an angle to the first shaft, means connecting the two shafts to transmit to the second shaft a rocking movement, means for varying the tension of the spring, said means including an arbor mounted in the casing and extending outward therefrom, and a finger attached to the arbor outside of the casing to permit manually operating the same. 90

2. An operating means for speed-indicators, comprising a casing or support, a shaft mounted to reciprocate therein, means for moving the shaft inward, a spring tending to move the shaft outward, a second shaft for transmitting the movement of the first-named shaft, said second shaft being mounted in the casing at an angle to the first shaft, means connecting the two shafts to transmit to the second shaft a rocking movement, means for varying the tension of the spring, said means including an arbor mounted in the casing and 95

extending outward therefrom, a finger attached to the arbor outside of the casing to permit manually operating the same, and an auxiliary casing carried by the first-named casing
5 and having a removable top or cover, said finger being located in the auxiliary casing.
In testimony whereof I have signed my

name to this specification in the presence of two subscribing witnesses.

CLARENCE E. KELLY.
